UNITED STATES PATENT OFFICE

RALPH D. MERSHON, OF NEW YORK, AND PERCY A. ROSS, OF YONKERS, NEW YORK;
SAID ROSS ASSIGNOR TO SAID MERSHON

ELECTROLYTIC APPARATUS

Application filed April 30, 1927. Serial No. 187,721.

In the operation of electrolytic condensers the filmed electrodes (of aluminum or other suitable metal) should be wholly covered by or immersed in the electrolyte, as it has been found that if the filmed surface extends out of the electrolyte corrosion occurs at the point of emergence. With an aqueous electrolyte there is always more or less evaporation and some electrolytic decomposition. Water vapor thus produced can be condensed and returned as liquid to the electrolyte, but loss of vapor that may occur by leakage, together with the loss by decomposition, may in the course of time bring the surface of the electrolyte below the top of the electrodes or plates.

Our present invention is designed to provide automatic indication of the height of the electrolyte, giving timely warning of danger conditions so that the amount of electrolyte may be increased, as by the addition of water, before serious damage, or any damage, has been caused. Another object is to provide automatic means by which the warning may take the form of disconnection of the apparatus from the line or other source of current with which it is operating when the electrolyte falls to a predetermined level. To these and other ends the invention comprises the novel features hereinafter described.

In carrying out the invention in the preferred manner we provide the condenser tank with a vapor outlet tube so arranged that its lower end is normally submerged in the electrolyte, and we permit or cause the temperature of the electrolyte to rise, for example, as a result of electrical losses in the apparatus, to a point at which there is more or less ebullition, preferably vigorous. The ebullition or boiling is primarily intended to produce rapid circulation or flow of the electrolyte for the purpose of dislodging or sweeping off any bubbles of gas that might adhere to the plates and permit corrosion to take place at the bubble boundaries, but in the present form of the invention we take advantage of the boiling condition by utilizing the concurrent rapid evolution of steam to operate or control the warning device or devices. For this purpose we provide, in connection with the vapor outlet or warning tube, means respon-

sive to the flow or escape of steam therefrom in such manner that when the flow of steam becomes excessive due to the electrolyte falling below and thereby opening the normally submerged lower end of the tube the desired warning will be given.

The embodiment outlined above is illustrated in the accompanying drawings, in which

Fig. 1 shows the apparatus diagrammatically, with the condenser in vertical cross section.

Fig. 2 is a detail view, partly in section, of a simple whistle which can be employed when an audible signal is desired.

Fig. 3 is a diagram illustrating a modification of the form shown in Fig. 1.

Figs. 4 and 5 illustrate the use of thermostatic means of more common form for controlling the system.

Fig. 6 shows a simpler form of the invention.

The plates or "anodes" 10, 11, immersed in the electrolyte 12, are connected in groups or sets to the terminals 13, 14 for connection with the source of current, not shown. The condenser is excited by direct current from a generator 15, the positive terminal of which is connected by wire 16 to the neutral point or center of the autotransformer or choke coil 17 across the condenser terminals 13, 14. The negative terminal of the exciting source is connected by wires 18, 18a and a fusible link 19 (for the purpose explained below) to the condenser cathode, which in the present instance is the tank or container 20, made of copper or other suitable non-filming metal.

For the purpose of conserving liquid which would otherwise be lost by evaporation of the electrolyte the tank 20 may be equipped with a radiator or condenser, say in the form of a coiled pipe 21. As the steam rises in the pipe it loses heat by radiation and the resulting condensate runs back into the tank, thereby reducing or minimizing the possible loss by evaporation. At the same time the condenser pipe or radiator, being open to the atmosphere, prevents rise of pressure in the tank above a value determined by the friction head of the vapor in the pipe. Inasmuch as it is not always, if ever, possible to re-

duce the loss of vapor to zero the surface of the electrolyte may eventually fall below the tops of the plates. To give warning of the approach of this condition we provide a 5 warning tube 22, the inner or intake end of which is located at a suitable point with respect to the tops of the plates, say a short distance above the same. The outer or outlet end is bent downwardly to keep out dust and 10 other foreign matter that might contaminate the electrolyte, and connected with the outlet end is a simple whistle 23. It will be understood that by reason of the condenser 21 the pressure in the tank, due to the friction 15 head in the condenser, is too low to force liquid out of the warning tube.

So long as the lower end of the tube 22 is submerged in the electrolyte the only steam escaping from the tube is that resulting from 20 evaporation from the small surface area of the liquid in the tube and is therefore relatively slight, even when the electrolyte is boiling vigorously. If, however, the surface of the electrolyte descends far enough to open 25 the tube the steam immediately escapes in a visible jet and at a rate fast enough to blow the whistle 23, thereby warning the attendant of the approach of danger conditions so that he may add water before damage occurs. Or, 30 if the whistle is omitted, the jet of steam issuing from the tube will give sufficient visible warning.

In order to positively protect the condenser in case the warning is unheeded we 35 provide in the condenser leads a circuit breaker, indicated diagrammatically at 24, normally held closed by a relay 25 connected to the exciting source 15 and across the fusible link 19, which latter, it will be remembered, is in series with the tank 20 serving as the condenser cathode. The link is shown mounted across the bore of the tubular member 26 of thermally and electrically non-conducting material, connected at the top to the 40 outlet end of the warning tube and at the bottom to the warning whistle 23. The link being made of metal which is fusible at a temperature less than or no higher than that of the boiling electrolyte, it will be seen that ab- 45 normal flow of steam due to uncovering the lower end of tube 22 will sooner or later melt the link, thereby opening the relay circuit and deenergizing the relay, whereupon the circuit breaker 24 operates and opens the ex- 50 ternal circuit of the condenser. The opera- 55 tion of the relay may also light a lamp, or sound a horn, or both. For such purpose a lamp 27 and horn 28 are shown connected across the condenser terminals 13, 14 through 60 normally open contacts 29. When the relay is deenergized its armature swings over and bridges the contacts, thereby closing the cir- 65 circuit of the lamp and horn.

If desired, one or more other warning tubes, as 30, 31, 32, may be provided, extend-

ing to different depths in the electrolyte to give successive visible or audible warnings or both as the surface of the electrolyte falls. The whistles with which the tubes are shown equipped may differ in pitch or other quality so that as the tubes are opened in succession the resultant note or tone will change in a distinctive manner.

In the modification illustrated in Fig. 3 the tubular member 26a in which the whistle 23 and fusible link 19 are mounted (one below the other) has a side outlet 33 for steam and has at its bottom tapered to form a small cavity into which extend the normally open contacts 34. The latter are in series with the normally de-energized relay 25a. The circuit breaker 24a is of any suitable type such that when the lever 24b, which serves as the relay armature, is actuated by the energized relay the external circuit of the condenser (not shown in Fig. 3) will be broken. Now when the link 19 is fused the puddle of metal thus deposited in the bottom of the member 26a will bridge the contacts 34, thereby causing current to flow through the relay from the exciting source 15. The relay, thus energized, actuates the circuit breaker lever 24b, which at the same time bridges the contacts 29 and causes current to flow through lamp 27 and horn 28. In 95 the arrangement shown in Fig. 3 the link 19 is not in the exciting circuit, the wire 18 going directly to the condenser cathode, not shown.

Instead of fusible members we may use 100 thermostatic means of more ordinary type, as in Figs. 4 and 5, for example. In the former, in which the relay 25b and circuit breaker 24c are the same as in Fig. 1, abnormal flow of steam heats the bimetallic bar 35, thereby causing it to flex out of engagement with the contact 36 and open the relay circuit. In Fig. 5, in which the relay 25c and circuit breaker 24d are the same as in Fig. 3, the bar 37 flexes into engagement with contact 38 105 when heated, thereby closing the relay circuit.

In some cases the simple system shown in Fig. 6 may be employed. In this figure the warning tube 22a is forked and the non-conducting body 26b carries two fusible links, 40, 41, in series with the condenser leads 42, 43. The relay 25d is connected across the leads 42, 43, between the links and the condenser, not shown. When the links are fused by abnormal flow of steam through the warning tube, not only is the external circuit of the condenser broken but the relay is also de-energized and its armature swings over to contact 44, thereby closing the circuit of lamp 27 and horn 28. And of course the third link, 45, is in the exciting circuit, in the present instance in the negative lead 18 from the exciting source 15, so that when link 45 is fused the exciting circuit 120 125 130

will be opened. It will be understood that if desired the three links may be arranged one above the other in the same bore instead of in separate bores or passages.

It is to be understood that the invention is not limited to the features herein specifically described but can be embodied in other forms without departure from its spirit as defined by the appended claims. Nor is the invention limited to use with electrolytic condensers or other electrolytic apparatus, but may be used, generally, wherever account is to be taken of variation in level of a heated liquid undergoing rapid evaporation in a substantially closed vessel.

We claim—

1. In an electrolytic condenser, a vessel, a vaporizable electrolyte therein, filmed electrodes immersed in the electrolyte, a tube open at both ends having one end immersed in the electrolyte so as to be closed thereby until uncovered by fall of the electrolyte surface due to loss of the same, and an electric circuit controlled by abnormal flow of vapor through said tube.

2. In an electrolytic condenser, a vessel, an aqueous electrolyte therein, filmed electrodes immersed in the electrolyte, a tube having an open end immersed in the electrolyte so as to be closed thereby until uncovered by fall of the electrolyte surface due to evaporation, an electric circuit controlled by abnormal flow of steam through said tube, and means controlled by said circuit to open the external circuit of the electrolytic apparatus when said abnormal flow occurs.

3. In an electrolytic condenser, a vessel, an aqueous electrolyte therein, filmed electrodes immersed in the electrolyte, a tube having an open end immersed in the electrolyte so as to be closed thereby until uncovered by fall of the electrolyte surface due to evaporation, a heat-responsive body arranged in the path of steam flowing through said tube, whereby to be exposed to abnormally high flow of steam due to uncovering of the tube inlet by fall of the electrolyte, and an electric circuit controlled by the said body.

4. In an electrolytic condenser, a closed vessel, an aqueous electrolyte therein, filmed electrodes immersed in the electrolyte, means associated with the vessel to condense vapor liberated from the electrolyte and return the condensate to the electrolyte and prevent excessive rise of pressure in the vessel; and means for opening the external circuit of the condenser when the surface of the electrolyte falls below a predetermined level; said circuit-opening means comprising a tube having one end immersed in the electrolyte above said predetermined level, and a heat-responsive circuit-controlling body in the path of vapor conveyed by said tube whereby to be exposed to abnormal flow of vapor through

said tube incident to uncovering of the immersed end of the tube by loss of electrolyte.

5. In an electrolytic condenser, a vessel, an electrolyte therein, said vessel having a vapor outlet adapted to discharge an abnormal flow of gas or vapor upon fall of the electrolyte to a predetermined level due to loss of electrolyte in gaseous or vapor form, and warning means including a heat-responsive device in the path of vapor flowing through said outlet, dependent for operation upon the heat of said abnormal flow of vapor.

In testimony whereof we hereto affix our signatures.

RALPH D. MERSHON.
